Inventor:

E. E. Davis

UNITED STATES PATENT OFFICE.

EVIN E. DAVIS, OF TAMA CITY, IOWA.

WATER-FOUNTAIN FOR STOCK.

SPECIFICATION forming part of Letters Patent No. 263,323, dated August 29, 1882.

Application filed August 23, 1881. (No model.)

To all whom it may concern:

Be it known that I, EVIN E. DAVIS, of Tama City, county of Tama, and State of Iowa, have invented a Water-Fountain for Stock, of which 5 the following is a description.

The object of this invention is to utilize the water in mole or blind ditches by conveying it to proper drinking-receptacles within the reach of stock.

10 The figure represents a side view of the apparatus, partly in section, and in proper relation for operation to the mole or blind ditch.

It is customary to run mole or blind ditches upgrade, and the water which they collect 15 naturally runs to the lowest point in them.

At this lowest point I apply my fountain, and, as its discharge-spout is lower than some point in the ditch, when a sufficient amount of water has accumulated in the ditch it will run 20 from the spout into the drinking-receptacle.

My fountain consists of a log, A, closed at one end and having a bore, H. This log is driven into the ditch, which is represented by

25 G. Pipe B, coupling C, and spout D connect the log A with the drinking-receptacle F, which is on the surface I of the ground. The pipe, coupling, and spout may be galvanized iron tubing.

The operation is as follows: The water collected by the ditch gradually accumulates at 30 the fountain, which, as before stated, is at the lowest point in it. As it continues to accumulate it will back up in the ditch until its surface is on a level with the spout D, when it will run into the receptacle F, as shown by 35 the arrow E.

What I claim, and desire to secure by Letters Patent, is—

The combination of the log A, pipe B, coupling C, and spout D, substantially as described. 40

EVIN E. DAVIS.
